US0D1085726S

(12) **United States Design Patent** (10) **Patent No.:** **US D1,085,726 S**
(45) **Date of Patent:** **** Jul. 29, 2025**

(54) **LID**

(71) Applicant: **KREATE BRANDS LLC**, Findlay, OH (US)

(72) Inventors: **Nickolas Reinhart**, Sarasota, FL (US); **Joe Klein**, Findlay, OH (US); **Ben Sayalith**, Findlay, OH (US)

(73) Assignee: **KREATE BRANDS LLC**, Findlay, OH (US)

(**) Term: **15 Years**

(21) Appl. No.: **29/935,034**

(22) Filed: **Mar. 29, 2024**

(51) LOC (15) Cl. **03-01**

(52) U.S. Cl. **USPC D3/318**

(58) **Field of Classification Search**

USPC D3/272-273, 302, 318, 323;
D9/424-425, 429, 432, 435; D32/54
CPC B65D 1/22; B65D 2543/00027; B65D
2543/00194; B65D 21/0233; B65D
2543/00296

See application file for complete search history.

(57) **CLAIM**

The ornamental design for a lid as shown and described.

DESCRIPTION

FIG. 1 is a top perspective view of a lid showing our new design.

FIG. 2 is a bottom perspective view of the lid showing our new design.

FIG. 3 is a front view of the lid showing our new design.

FIG. 4 is a back view of the lid showing our new design.

FIG. 5 is a right side view of the lid showing our new design.

FIG. 6 is a left side view of the lid showing our new design.

FIG. 7 is a top view of the lid showing our new design; and,

FIG. 8 is a bottom view of the lid showing our new design.

The broken lines shown in the Figures show portions of the lid that form no part of the claimed design.

1 Claim, 6 Drawing Sheets
